END STOP FOR SLIDE FASTENERS

Martin Winterhalter, Morcote, Switzerland

Application January 23, 1945, Serial No. 574,073
In Switzerland October 6, 1944

6 Claims. (Cl. 24—205.11)

1

This invention relates to separable slide fasteners and more particularly to the provision of an improved end stop for limiting the movement of the slider longitudinally of the stringers in one direction and for uniting the two stringers at one end thereof.

For permanently uniting the ends of the stringers of a separable fastener usually an end stop is used which in case of metallic fastener elements is formed as a metallic clip attached to the two stringer tapes for securing the adjacent edges of the tapes one to the other. In case of non-metallic fastener elements consisting of thermoplastic material the end stop can also be made of such material and is attached to the tapes by cementing or by means of metallic pins penetrating through the tapes.

With an end stop of this kind, when the slider is to be changed, for example when the slider is broken or another type of slider is desired to be used with the stringers, the end stop must be removed from the tapes in order to enable the new slider to be pulled on the stringers. Such removal however is difficult or even impossible and the tapes can easily be hurt; usually after the removal of an end stop, a new one must be attached to the tapes, since the old end stop cannot be used a second time.

An object of the present invention is the provision of a separable fastener, particularly of the type having fastener elements fixed upon the tapes by die-casting, and comprising an end stop which need not be removed for changing the slider, but which can remain on the tapes.

According to the invention the end stop for uniting the two tapes at one end of the stringers comprises two parts which are each secured to one tape by die-casting and coupled to each other by means of a clamp inserted in the two parts. In this case, for changing a slider only the clamp must be removed from the two parts of the end stop, while the two parts themselves remain on the tapes, and since then the two stringers are not united any more, a new slider can be readily placed on the stringers. Accordingly, it is not necessary to remove a member which is secured to the tapes and these latter are not injured by disengaging the coupling clamp from the two parts of the end stop.

Certain preferred embodiments of my invention are illustrated in the accompanying drawings, in which:

Fig. 1 is a plan view of a part of a fastener provided with the improved end stop.

Fig. 2 is a plan view of the end of the stringers with the end stop on an enlarged scale.

Fig. 3 is a longitudinal section along the line III—III of Fig. 2.

Fig. 4 is a transverse section through the end stop along the line IV—IV of Fig. 2.

2

Fig. 5 is a transverse section through the end stop before securing the clamp to the two parts of the end stop.

Figs. 6 and 7 are transverse sections through a modified form of an end stop before and after securing the coupling clamp to the two parts thereof.

Figs. 8 and 9 show a further modification of an end stop before and after securing the coupling clamp.

Figs. 10 and 11 are transverse sections of a still further modified end stop before and after securing of the coupling clamp.

Fig. 12 is a plan view of the two parts of the end stop according to Fig. 2 without the coupling clamp.

Fig. 13 is a similar view of the two parts of the end stop from the opposite side.

Figs. 14 and 15 show a fastener element seen from two opposite sides.

The separable fastener shown in Figs. 1 to 5 comprises fastener element supporting tapes 1 and 2 having and edge bead 3 to which the fastener elements 4 are directly secured by means of die-casting or pressure casting. For uniting the two tapes at that end of the fastener which remains closed there is provided an end stop S formed of two separate parts 5 and 6 which consist of the same material as the fastener elements 4. These parts 5 and 6 are die-cast on the tapes 1 and 2 in the same casting operation together with the elements 4. The fastener elements and the end stop can consist of metal, such as cast zinc, or of a thermoplastic material, as for example of a high molecular condensation product such as known under the name of nylon, or the like.

The fastener elements 4 comprise a coupling head which is provided on opposite sides with coupling projections formed as ribs and with coupling sockets formed as grooves. Referring to Figs. 2, 3, 14 and 15, the coupling head of the elements is provided on one side with two ribs 7 and 8 and with two grooves 9 and 10, while the opposite side of the coupling head is provided with two ribs 11 and 12 and with two grooves 13 and 14. The ribs 8 and 12 extend from one side face of the element to surfaces 15 and 16, respectively, each of these surfaces being positioned at substantially one half of the width of the element and parallel with the common plane of the two tapes 1 and 2. The rib 7 extends from the opposite side of the element to a surface 17 also situated at substantially one half of the width of the element and parallel with the common plane of the two tapes 1 and 2. The rib 11 extends from the same side of the element to the surface 16. The groove 10 extends through the same width as the rib 8 from one side face of the element to the surface 17, while from this

surface 17 the groove 9 extends through the same width as the rib 7 to the opposite side face of the element. On the other side of the coupling head the groove 13 extends through the same width as the rib 11 from one side face of the element to the surface 16, and the groove 14 extends from the opposite side face of the element to a surface 18, also situated at substantially one half of the width of the element.

When the fastener elements are coupled by means of a usual slider 19 (Fig. 1), the ribs 7 and 8 of one element of a stringer penetrate into the grooves 13 and 14 of one adjacent element of the other stringer and the ribs 11 and 12 of the first element penetrate into the grooves 9 and 10 of the other adjacent element. Simultaneously with this engagement of cooperating ribs and grooves, the surfaces 15 and 17 of one element pass over the surfaces 18 and 16 of the adjacent element. These surfaces extending transversely to the ribs and grooves prevent a disengagement of two coupled elements in both directions at right angles to the common plane of the two tapes 1 and 2.

The two parts 5 and 6 of the end stop are also provided with interengaging projections and recesses which prevent a relative displacement of the two parts in longitudinal direction, and cooperating surfaces extending parallel with the common plane of the two tapes 1 and 2 which prevent a relative displacement of the two parts at right angles to the said plane. The part 5 of the end stop is provided with a projection 26 which extends from one side face of the part to a surface 24 situated substantially at one half the width of the part, which surface is parallel with the common plane of the two tapes 1 and 2. This projection 26 penetrates into a recess 22 of the part 6 which also extends from one side face of the part to a surface 23, which surface is situated substantially at one half of the width of the part and is parallel with the common plane of the two tapes. The part 6 also is provided with a similarly positioned surface. A projection 25 extends from this surface 24, to one side face of the part, and a recess 26 extends from the surface 24 towards the opposite side until the other side face of the part. A further surface 27 of the part 5 extends at substantially one half of the width of the part and parallel with the common plane of the two tapes 1 and 2. This surface 27 forms one side of a projection 28 and one side of a recess 29. When the two parts 5 and 6 of the end stop are joined together the projection 25 engages into the recess 29 and the projection 28 into the recess 26, while the surface 24 of one part passes over the surface 27 of the other part. Since the surfaces 24 and 27 of the part 5, and the surfaces 23 and 26, of the part 6 are facing towards opposite sides the joined parts 5 and 6, owing to these surfaces passing one over the other, cannot move relatively to each other transversely to the common plane of the tapes 1 and 2, while a relative displacement of the two parts 5 and 6 in longitudinal direction with regard to the fastener is prevented by the engagement of the projection 26 of the part 5 into the recess 22 of the part 6.

The joined parts 5 and 6 of the end stop are coupled by a U-shaped metallic clamp 30. The two branches 30a of the clamp penetrate through slots 31 and 32 provided at opposite side faces of the two joined parts, while the central portion 33 of the clamp is partially sunk in recesses 34 and 35 provided on one face of the two parts 5 and 6. As shown in Fig. 5, the clamp is inserted with its two branches into the slots 31

and 32, the branches being stuck through the tapes 1 and 2. The branches of the clamp are slightly longer than the height of the two parts 5 and 6 of the end stop and after insertion into the slots 31 and 32 the projecting ends of the branches are upset or riveted in order to obtain a rigid connection between the clamp and the two parts 5 and 6. When the two parts of the end stop are die-cast of a thermoplastic material, such as nylon or polyamide, which is slightly elastic and softer than the metal of the clamp, the upsetting of the ends of the clamp produces a compression of the material of the parts 5 and 6 as shown in Fig. 4, so that the upset or riveted ends of the clamp overlie the edges of the parts 5 and 6 and firmly secure the clamp to the two parts. These latter cannot separate any more and remain in their interengaged position.

The central portion 33 of the clamp 30 projecting beyond the outer face of the two parts 5 and 6 serves as stop for limiting the movement of the slider 19, as shown in Fig. 1. Owing to this projecting clamp the slider cannot be lowered so far that the wedge portion 36 of the slider abuts against the end stop, or that the two parts 5 and 6 of the end stop are urged into the diverging guide passages of the slider; accordingly the two parts 5 and 6 are not subjected to any effort tending to separate them. In this manner, the clamp 30 itself is never subjected to any considerable stress, since its purpose is only to hold the two parts 5 and 6 together, but these parts are not subjected to any effort tending to pull them out of engagement with each other.

When a new slider is to be engaged on the stringers of the fastener, the clamp can be removed from engagement with the two parts 5 and 6 by means of an appropriate tool. Then the old slider can be pulled off from the stringers and a new one can be engaged thereon without requiring to remove the end stop members 5 and 6 from the tapes 1 and 2, which would be impossible with the members die-cast directly on the tapes.

The part 6 of the end stop on the tape 2 has its side facing the last fastener element 4 provided with coupling ribs 7 and 8, and with coupling grooves 9 and 10, like one side of the coupling head of the fastener elements 4. When the two stringers are coupled by means of the slider 19, the ribs 7 and 8 of the part 6 engage with the grooves 13 and 14 of the last fastener element 4 on the tape 1, and the ribs 11 and 12 of this element engage with the grooves 9 and 10 of the part 6.

Referring to Fig. 1, the upper open ends of the stringers are each provided with an end stop 40 which is also die-cast on the tapes 1 and 2 in the same casting operation together with the fastener elements 4 and the lower end stop 5 and 6. The two end stops 40 have a length equal to the distance between two successive fastener elements, and for aesthetical reasons, the opposite side faces of the two stops 40 are formed with the outer contour of two fastener elements which are rigidly connected by a central web 41. These stops 40 limit the upward movement of the slider, since they abut against each other in the interior of the slider and can accordingly not pass out of the guide channel thereof.

When the end stop 5, 6 is not formed of thermoplastic material, but of metal, as for example of cast zinc, the ends of the clamp 30

cannot be pressed into the parts 5 and 6 simply by an upsetting or riveting operation, since the material of the end stop parts is in this case too hard. As shown in Figs. 6 and 7, the parts 5 and 6 are provided with notches 31 into which the material of the clamp ends can penetrate when these ends are upset, so as to produce a firm connection between the clamp and the two parts 5 and 6.

In the example according to Figs. 8 and 9 the branches of the clamp 30b are not passed through slots in the outer faces of the two parts of the end stop, but through tapering holes 38 provided in the two parts 5 and 6. When these parts consist of thermoplastic material, this latter is compressed upon forcing the branches of the clamp into the holes 38 of decreasing diameter, thus producing a frictional engagement between the clamp and the two parts. For greater security of the connection the ends of the branches of the clamp are riveted as shown in Fig. 9.

Referring to Figs. 10 and 11, the end stops 5 and 6 are made of cast zinc. The holes for insertion of the clamp are cylindrical and formed with enlarged ends 39 into which the ends of the branches can be riveted. In this example the central web of the clamp is entirely sunk into the recesses 34 and 35 of the parts 5 and 6, and accordingly does not act as limiting abutment for the movement of the slider. This latter is stopped by abutment of the wedge 36 against the end stop members 5 and 6.

The advantages of the described fastener are that the stringers can be cast together with the end stops on both ends thereof by a single casting operation in the same die and the two part end stop 5, 6 allows to readily exchange a slider for another one. Further, when the fastener elements and the end stop members consist of thermoplastic material, the coloring of the fastener elements and of the end stop member is absolutely identical, since they are cast simultaneously in a single operation and accordingly from the same supply of material.

The particular slide fastener disclosed is merely illustrative of one type of fastener which may be employed, and it is to be understood that the above described structure is in no wise limiting, and I desire to comprehend within my invention all modifications included within the scope of the appended claims.

I claim:

1. The combination with separable fastener stringers having a slider, of an end coupling comprising a coupling member fixedly secured to one stringer and a coupling member fixedly secured to the other stringer, said coupling members having interengaging projections and recesses releasable in a direction cross-wise of said stringers, said interengaging projections and recesses interlocking said coupling members against substantial relative movement in both directions longitudinally of the stringers, and normal to the plane of the stringers, both of which members are adapted to pass through the slider to permit removal of the latter from the stringers, and a removable part carried by said members and secured to both of them for fixedly holding them against movement in all directions whereby to hold said interlocking portions of said members in engagement in all positions of the slider longitudinally of the stringers, said part having a portion serving as an end stop for the slider.

2. The combination according to claim 1 in which the removable part is in the form of a U-

shaped member embracing the two coupling members.

3. The combination according to claim 1 in which the removable part is in the form of a U-shaped member embracing the two coupling members, with the opposite legs of the U extending through the stringers.

4. The combination according to claim 1 in which the removable part is in the form of a U-shaped member having opposite legs and a base, the coupling members having exterior grooves for receiving said legs and base with said U-shaped member in embracing relation to said coupling members, with said base extending across said coupling members and said legs lying at those sides of said coupling members which are remote from each other, the terminal portions of said legs extending inwardly toward each other at the sides of said coupling members opposite said base for engaging said coupling members for securing said U-shaped member in assembled relation therewith.

5. The combination with separable fastener stringers having a slider, of an end coupling comprising a coupling member fixedly secured to one stringer and a second coupling member fixedly secured to the other stringer, said coupling members having interengaging projections and recesses releasable in a direction cross-wise of said stringers, said interengaging projections and recesses interlocking said coupling members against substantial relative movement in directions longitudinally of the stringers and normal to the plane of the stringers, both of which members are adapted to pass through the slider to permit removal of the latter from the stringers, said members being formed with exterior grooves collectively forming when the members are in assembled relation an exterior groove having at least a portion extending over both members transverse to the stringers, a U-shaped clamp embracing said members for holding them against separation, the legs of said clamp passing through the stringers, interior edge portions of said U-shaped clamp being received in said portion of said groove and fitting its opposite lateral walls for relieving said interlocking portions of said members against strains longitudinally of the stringers, and exterior edge portions of said U-shaped clamp projecting from said groove for acting as an end stop for the slider, the free end portions of said U-shaped clamp extending toward each other over the sides of said members opposite said portion of said groove for securing said clamp to said members, said clamp being of deformable material for permitting its ready removal from said members.

6. The combination according to claim 1 in which each of the coupling members is formed with a perforation, and the removable part is in the form of a U-shaped member having opposite legs received in said perforations.

MARTIN WINTERHALTER.
